VACUUM BOTTLE

Charles L. Seltz, Ann Arbor, Mich., assignor to King-
Seeley Thermos Co., Ann Arbor, Mich., a corporation
of Michigan

Filed May 8, 1964, Ser. No. 79,888

Term of patent 14 years

(Cl. D58—8)

FIGURE 1 is a perspective view of a vacuum bottle showing my design;

FIGURE 2 is a side elevational view thereof;

FIGURE 3 is a side elevational view taken at right angles to FIGURE 2;

FIGURE 4 is a top plan view;

FIGURE 5 is a bottom plan view;

FIGURE 6 is a detail sectional elevational view taken substantially on the plane indicated by line 6—6 in FIGURE 2 locking in the direction of the arrows;

FIGURE 7 is a detail sectional view taken substantially on the plane indicated by line 7—7 in FIGURE 3, looking in the direction of the arrows;

FIGURE 8 is a detail sectional view taken substantially on the plane indicated by line 8—8 in FIGURE 4; and

FIGURE 9 is an enlargement of the portion enclosed by circle 9 shown in FIGURE 1.

I claim:

The ornamental design for a vacuum bottle, substantially as shown.
